(57) **CLAIM**

The ornamental design for tractor tool box, as shown and
described.

DESCRIPTION

FIG. 1 is a perspective view of a tractor tool box showing my
new design;

FIG. 2 is a top plan view thereof;

FIG. 3 is a rear elevational view thereof; and,

FIG. 4 is a right side elevational view, the left side eleva-
tional view being a mirror image thereof.

The broken line showing of environment is for illustrative
purposes only and forms no part of the claimed design.
